UNITED STATES PATENT OFFICE

90,904

DESIGN FOR A TIRE COVER OR SIMILAR ARTICLE

George Albert Lyon, Asbury Park, N. J.

Application January 25, 1933. Serial No. 46,973

Term of patent 14 years

To all whom it may concern:

Be it known that I, GEORGE ALBERT LYON, a citizen of the United States, and residing in the city of Asbury Park, in the county of Monmouth and State of New Jersey, have invented a new, original, and ornamental Design for a Tire Cover or Similar Article, of which the following is the specification, reference being had to the accompanying drawing forming a part thereof.

On the drawing:

Figure 1 is a perspective view of my spare tire cover.

Figure 2 is a top view of the cover while in a vertical position and partly in section so as to more clearly show the contour of the side portion and tread covering portion of the cover.

The two views clearly illustrate the novel contour of my tire cover which is especially adapted for use with spare tires disposed on a wheel with an outwardly projecting central wheel hub.

I claim:

The ornamental design for a tire cover or similar article as shown and described.

GEORGE ALBERT LYON.
